UNITED STATES PATENT OFFICE.

FRANCIS J. MARTHY, OF HAZLETON, PENNSYLVANIA.

TENSIONING DEVICE.

Application filed March 25, 1925. Serial No. 18,205.

This invention relates to tensioning devices adapted to be employed in combination with tuning pins for piano strings.

The tuning pin of an instrument is ordinarily mounted within an opening provided in the wrest plank or pin block but such opening becomes enlarged due to the rotation of the pin during tuning and also due to strains caused by the tension of the string so that it is difficult to hold the pin against rotation after a predetermined number of tunings. Because of such defect in the pin block it is necessary to set the pins but such setting seldom if ever can be effected after any length of time because of the defective wrest planks and because of the twisting of the pins.

An object of the invention is the provision of a device adapted to be employed in connection with tuning pins whereby the strings of the instrument may be easily, accurately and finely adjusted and securely held in their adjusted positions.

A further object of the invention is the provision of a device adapted to be employed in connection with tuning pins for pianos and in which the pin is held against movement after its adjustment and upon which is mounted a removable sleeve to which the string is secured for finely adjusting the tension of the strings which will maintain the tension.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a fragmentary view in elevation showing my invention applied to the metal plate of the piano.

Figure 2 is a transverse vertical section taken through one of the pins.

Figure 3 is a view in perspective of the preferred form of my invention showing the parts in detached relation.

Figure 4 is a view in perspective of a modified form of the invention.

Figure 5 is a view showing the modified

form of the invention shown in Fig. 4 as applied to the usual makes of the pianos now in use.

Figure 6 is a view in perspective of the sleeve associated with the pins shown in Figures 4 and 5.

Referring more particularly to the drawings, 10 designates a metal plate of a piano which is provided with a plurality of sleeves 11 integrally formed with the plate. Each of the sleeves is provided with a passage 12 in which is mounted a tuning pin 13. This pin has one end threaded as shown at 14 adapted to receive a nut 15 which engages a washer 16 abutting a shoulder 40 on the pin 13 so that the washer is slightly spaced from the free end of the sleeve. The pin 13 has a toothed wheel or flange 17 rigidly attached thereto and adapted to engage the outer face of the metal plate 10 and cooperate with the nut 15 to prevent displacement of said pin.

A spring pressed pawl 18 secured to the metal plate 10 is adapted to engage the teeth of the flange 17 and lock the pin against rotation.

The pin at 19 is provided with a spiral screw or thread which is of the multiple trapezoidal or square thread with considerable pitch.

Mounted on the threaded portion 19 is a sleeve 20 having a collar 21 in which is formed a recess or countersunk portion 22 adapted to receive a hub 23 on a nut 24 which engages the threads 25 on the pin 19. The sleeve 20 is provided with threads 26 adapted to engage the threads on the portion 19 of the pin. The pin at its outer extreme end is square in cross section as shown at 27 which is adapted to be engaged by any suitable tool. The nut 24 has a hexagonal conformation likewise adapted to be engaged by a suitable tool for turning the same. The collar 21 is provided with a perforation 28 in which is adapted to be inserted the end of a piano string 29.

In Figure 4 is shown a modified form of the invention and in which the portion 19a is devoid of threads but provided with a pin 30 which projects laterally from diametrically opposite points and which projects through curved slots 31 in a sleeve 32. The sleeve 32 has a collar 33 provided with a perforation 34 adapted to receive a piano wire 29. The collar 33 is located inter-

mediate the ends of the sleeve 32. The pin 13^a in this case is also provided with a threaded end 14, a threaded portion 25 adapted to be engaged by a nut for adjusting and locking the sleeve 32 against movement. The end of the pin is square in cross section adapted to be engaged by any suitable tool. The toothed annular flange 17 is also employed and is adapted to be engaged by the pawls 18 with the inner end of the sleeve 32 abutting the member 17.

In Figure 5 is shown the modified form secured to the metal plate of the piano whereby the usual forms of metal plates may be adapted with the present invention. In such a case an enlarged opening 35 is provided in the plate 10^a through which is inserted a metal sleeve 11^a. This sleeve is provided with a flange 36 upon which is pivotally mounted a spring pressed pawl 37 adapted to engage the teeth of an annular flange 17^a formed integrally with the pin 13^a. The sleeve 11^a is externally threaded and a nut 38 engaging the threads on the sleeve is adapted to lock the sleeve to the metal plate 10^a in conjunction with the annular flange 36. The pin 13^a has a threaded end 14 upon which is screwed a nut 15 for forcing the washer 16 in rigid engagement with the shoulder 40 on the inner end of the pin 10^a. The washer 16 and wheel or flange 17^a cooperate to prevent displacement of the pin.

The operation of my device is as follows: Either construction as shown in Figure 2 or 5 may be employed and the pins 13 or 13^a are locked in place as has been explained by means of the toothed annular flange 17 and the nut 15 and washer 16 with the nut 40 located at one end of the sleeve 11 or 11^a and the toothed flange 17 in engagement with one face of the metal plate 10 or 10^a. The pin 13 or 13^a is rotated in the usual manner until substantially the pitch of the string is had whence the nut 24 is turned until the proper tension is placed upon the string to produce the exact tone desired. The nut 24 frictionally engaging the end of the sleeve 20 or the sleeve 32 causes the sleeve to be turned and since the string is secured to the sleeve the string will be further tensioned. As the nut 24 is revolved in the construction shown in Figure 3 the sleeve is also rotated to its engagement with the threads on the portion 19 of the pin while in Figure 4 the sleeve is revolved and maintained in its adjusted position through the pins 30 moving through the arcuately shaped slots 31 of the sleeve 32.

Having described the invention, this is claimed:

1. A tensioning device for piano strings comprising a tuning pin, a sleeve mounted on the pin for independent rotation, means for operatively connecting the sleeve with

the pin so that the sleeve may be revolved with the pin, and a nut threaded on the pin to frictionally contact with the sleeve for causing rotation of the sleeve independently of the pin when the nut is rotated, and means included in the pin, nut and sleeve for causing a differential speed of rotation between the nut and the sleeve.

2. A tensioning device for piano strings comprising a tuning pin, a sleeve mounted on the pin for independent rotation, means for operatively connecting the sleeve with the pin so that the sleeve may be revolved with the pin, and a nut threaded on the pin to frictionally contact with the sleeve for causing rotation of the sleeve independently of the pin when the nut is rotated, means for locking the pin against rotation in one direction, and means included in the pin, nut and sleeve for causing a differential speed of rotation between the nut and the sleeve.

3. A tensioning device for piano strings comprising a tuning pin, a sleeve mounted on the pin for independent rotation, means for operatively connecting the sleeve with the pin so that the sleeve may be revolved with the pin, and a nut threaded on the pin to frictionally contact with the sleeve for causing rotation of the sleeve independently of the pin when the nut is rotated, said sleeve being provided with means for securing the piano string to the same whereby the end of the piano string will be coiled on the sleeve during tensioning of the string, the operative means which connects the sleeve with the pin being constructed to cause a differential speed of rotation between the nut and the sleeve.

4. A tensioning device for piano strings comprising a metal plate provided with a plurality of hollow sleeves projecting rearwardly from said plate, a tuning pin mounted in each sleeve, the tuning pin being provided with a ratchet wheel forming a shoulder to engage one face of the metal plate, means cooperating with the wheel to prevent displacement of the pin from a sleeve, pawls to engage the ratchet wheel for preventing rotation of the pin in one direction, a sleeve rotatably mounted on the pin, and cooperating means on the pin and the sleeve for causing the sleeve to be moved longitudinally of the pin and permitting independent rotation of the sleeve on said pin, a nut threaded on the pin adapted to frictionally contact with the sleeve so that when the nut is rotated the sleeve will be revolved independently of the pin, and means for securing a piano string to the sleeve.

5. A tensioning device for piano strings comprising a metal plate provided with a plurality of hollow sleeves projecting rearwardly from said plate, a tuning pin mounted in each sleeve, the tuning pin be-

- ing provided with a ratchet wheel forming a shoulder to engage one face of the metal plate, means cooperating with the wheel to prevent displacement of the pin from a sleeve, pawls to engage the ratchet wheel for preventing rotation of the pin in one direction, a sleeve rotatably mounted on the pin, cooperating threads on the pin and on the sleeve for causing the sleeve to be moved longitudinally of the pin and permitting independent rotation of the sleeve on said pin, a nut threaded on the pin to frictionally contact with the sleeve so that when the nut is rotated the sleeve will be revolved independently of the pin, and means for securing a piano string to the sleeve. 6. A tensioning device for piano strings comprising a metal plate provided with a plurality of hollow sleeves projecting rearwardly from said plate, a tuning pin mounted in each sleeve, the tuning pin be-
ing provided with a ratchet wheel forming a shoulder to engage one face of the metal plate, an end of the pin being threaded and a nut screwed onto the threaded end of the pin for cooperating with the ratchet wheel to prevent displacement of the pin from the sleeve, pawls to engage the ratchet wheel for preventing rotation of the pin in one direction, a sleeve rotatably mounted on the pin, and cooperating means on the pin and the sleeve for causing the sleeve to be moved longitudinally of the pin and permitting independent rotation of the sleeve on said pin, a nut threaded on the pin adapted to frictionally contact with the sleeve so that when the nut is rotated the sleeve will be revolved independently of the pin, and means for securing a piano string to the sleeve. 25 30 35
- In testimony whereof I affix my signature.
